UNITED STATES PATENT OFFICE.

WILLIAM D. MOORE, OF CRESTON, IOWA.

MOLD FOR POURED CONCRETE BRICKS OR BLOCKS.

1,194,862.

Specification of Letters Patent. Patented Aug. 15, 1916.

Application filed April 11, 1916. Serial No. 90,394.

To all whom it may concern:

Be it known that I, WILLIAM D. MOORE, a citizen of the United States, residing at Creston, in the county of Union and State 5 of Iowa, have invented certain new and useful Improvements in Molds for Poured Concrete Bricks or Blocks, of which the following is a specification.

This invention relates to molds for poured 10 concrete bricks or blocks and is especially designed to provide a mold which can be easily and quickly assembled in a series of sections; and in which the bricks or blocks can be readily discharged and piled.

15 The main object of the invention is to construct a simple, economical, durable, and thoroughly efficient labor saving device in the method of making poured concrete bricks or blocks.

20 Another object of the invention is to provide molds made in sections in which the individual molds are rigidly and permanently fastened to the upper side or surface of a flexible base, said base having an oppositely downwardly extending flange and a laterally projecting flange at each side of the base which construction creates a great saving of time in assembling the molds and also in removing the brick from the molds, 25 as each section forms its own pallet, and the brick are discharged from the molds by simply inverting the molds and springing the back of the section.

A further object of the invention is to 35 provide molds for poured concrete bricks or blocks in sections, which may be connected together in series, in which the partitions separating the sections are removably connected to the base and ends of each section 40 and so constructed that the end of each section is clamped together and the partition plate is always held flush and level with the upper edge of each mold and serves to prevent the base or bottom of each mold section 45 from springing in a downward direction.

The foregoing and such other objects as 50 may appear from the ensuing description are attained by the novel features of construction and arrangement of parts, hereinafter fully described, illustrated in the accompanying drawings, and particularly pointed out in the claims appended hereto, it being understood that slight changes in the form, proportions, and minor details of the construction may be resorted to without de-

parting from the spirit or sacrificing any of the advantages of the invention.

In the accompanying drawings it will be seen that: Figure 1, is a perspective view of the improved device embodying my invention. Fig. 2, is a plan view showing one of the mold sections composed of seven molds with a partition plate secured thereto. Fig. 3, is a longitudinal section of the device shown in Fig. 2. Fig. 4, is a transverse sectional view of the same with the platform or support removed. Fig. 5, is a perspective view of the partition plate removed from the series of sections shown in Fig. 1, and Fig. 6, is a perspective view showing the 70 method of discharging the bricks or blocks from each section.

Similar numerals of reference are employed to designate corresponding parts throughout the several figures of the drawings.

In the embodiment of this invention as illustrated and which shows a preferred construction, the numeral 1 indicates a platform or support which may be used for holding 80 any suitable or desirable number of mold sections, each section as illustrated, including seven brick or block molds, and each section is preferably formed of sheet metal or steel of the desired gage, and consists of a flexible base 2, having oppositely integral 85 depending extensions 3, adapted to contact with each side of said platform or support and provided with opposite lateral integral projections 4 constituting handles, whereby 90 each section may be readily handled and the bricks or blocks easily and quickly discharged from the molds by simply inverting the molds and springing or slightly curving the back of the section, as clearly shown in Fig. 6. The individual molds forming a 95 part of each section consists of a right-angled sheet of metal 5 rigidly and permanently fastened to the flexible base 2, one mold of each section at one side thereof being formed of two right-angled sheets of metal 6 permanently secured to the said base, the vertical extension of each sheet of metal forming one of the side walls of the mold, and at the opposite ends of each section or series of molds an end partition plate 7 is employed for inclosing the end of the molds.

As shown in Figs. 1, 2, 3 and 5 there are seven molds in each section, and the bricks 110

are to be molded on edge. It will be understood however that any suitable number of individual molds may be utilized; depending upon their size or whether or not they are to be molded upon their sides or upon their ends.

Referring to Figs. 2, 3 and 5 it will be seen that the partition plate 7 which is also formed of sheet metal and is utilized for 10 closing and separating the ends of the molds of each section is provided at each end thereof with oppositely extending flanges 8, which contact with the outer side walls of each mold section and serve as stops for the 15 said walls, while a vertical portion 9 at each end of the plate 7 projects beyond the vertical side walls of each mold section, and forms means for handling the said plates, whereby they may be readily removed when 20 one section is disconnected from another. It will also be perceived by reference to Figs. 4 and 5, that the partition plate 7 is provided at its lower portion intermediate its length with a plurality of oppositely projecting integral flanges 10, which are adapted to contact with the underside of the base 2 of each mold section, and serve to prevent the molds from springing downward and at the same time holding the upper edge of the 25 partition plate perfectly level and even with the upper edges of each mold section so as not to interfere with the operation of troweling the face of the brick perfectly smooth.

It will be readily obvious from the foregoing that poured concrete bricks or blocks 35 can be quickly molded, since the sections can be rapidly assembled and filled and the bricks can be quickly piled, as they are handled but once and are discharged from the 40 molds directly into the pile, the said molds serving to cast the brick in, to off-bear the brick on, and used to pile the brick with.

Having thus described my invention what I claim and desire to secure by Letters Patent is:—

1. A mold section for poured concrete blocks, comprising a series of molds, a flexible base member having integral depending side walls at right angles thereto and an 50 integral lateral extension at each side there-

of, in combination with a partition plate for inclosing the ends of each mold, said plate having oppositely disposed flanges extending from each end of the plate and intermediate oppositely disposed flanges near the 55 bottom of the plate.

2. A mold section for poured concrete blocks, comprising a base member having integral depending side walls at right angles thereto and a lateral extension at each side 60 thereof, a series of molds formed of right-angled sheets of metal rigidly secured to said base member, in combination with a partition plate having oppositely disposed flanges extending from each end of the plate 65 and intermediate oppositely disposed flanges near the bottom of said plate.

3. Mold sections for poured concrete blocks, each section comprising a series of molds, a flexible base member having integral depending side walls at right angles thereto and an integral lateral extension at each side thereof, in combination with a partition plate for inclosing the ends of each mold, said plate having oppositely disposed 70 flanges at each end portion, a plurality of integral intermediate oppositely disposed flanges near the bottom of the plate, and a vertical portion at each end of said plate projecting beyond the side walls of each section. 75

4. Mold sections for poured concrete blocks, each section comprising a series of molds, a flexible base member having integral depending side walls at right angles thereto and an integral lateral extension at 80 each side thereof, said molds being formed of right-angled sheets of metal permanently secured to said base, one mold of each section at one side thereof being formed of two right-angled sheets of metal rigidly fastened to the base, in combination with a partition plate having oppositely disposed flanges at each end portion, a plurality of integral intermediate oppositely disposed flanges near the bottom of the plate adapt- 85 ed to fit beneath the base of each mold section, and a vertical portion at each end of said plate projecting beyond the side walls 90 of said sections.

WILLIAM D. MOORE.
